(57) CLAIM

The ornamental design for a comb unit assembly, as shown and described.

DESCRIPTION

FIG. 1 is a front, top and left-side perspective view of a comb unit assembly showing my new design, in an assembled state;

FIG. 2 is a front elevation view thereof;

FIG. 3 is a rear elevation view thereof;

FIG. 4 is a left side elevation view thereof;

FIG. 5 is a right side elevation view thereof;

FIG. 6 is an enlarged top plan view thereof;

FIG. 7 is an enlarged bottom plan view thereof;

FIG. 8 is rear, bottom and right-side perspective view thereof; and,

FIG. 9 is an exploded perspective view thereof, in a disassembled state.

The broken lines in FIG. 9 depict portions of the comb unit assembly that form no part of the claimed design.

1 Claim, 9 Drawing Sheets
